UNITED STATES PATENT OFFICE.

CHARLES HANLEY JOHNSON AND WILLIAM RUSSELL JOHNSON, OF JERSEY CITY,
NEW JERSEY.

DUPLEX BOILER-GAGE.

1,374,081.

Specification of Letters Patent.

Patented Apr. 5, 1921.

Application filed July 1, 1920. Serial No. 393,258.

To all whom it may concern:

Be it known that we, CHARLES H. JOHNSON and WILLIAM RUSSELL JOHNSON, both citizens of the United States, and residents 5 of Jersey City, in the county of Hudson and State of New Jersey, have invented a new and Improved Duplex Boiler-Gage, of which the following is a full, clear, and exact description.

10 The object of the invention is to provide a new and improved boiler gage for use on stationary or locomotive boilers and arranged to remain in service even in case one of the glasses should break.

15 Another object is to allow convenient replacing of a broken glass without interrupting the use of the gage.

With these and other objects in view, the 20 invention consists of certain novel features 20 of construction, as hereinafter shown and described and then specifically pointed out in the claims.

A practical embodiment of the invention 25 is represented in the accompanying drawings forming a part of this specification, in which similar characters of reference indicate corresponding parts in all the views.

Figure 1 is a front elevation of the improved duplex boiler gage with parts shown 30 in section;

Fig. 2 is a side elevation of the same; and

Fig. 3 is a sectional plan view of the same on the line 3—3 of Fig. 2.

The body 10 of the duplex boiler gage is 35 preferably made of metal and is provided with two compartments 11 and 12 separated by a partition 13 common to both compartments. The sides of the compartments 11 and 12 are formed by glass plates 14 and 15 sufficiently strong to withstand any boiler 40 pressure, and the outer faces of the plates 14 and 15 are provided with vertically disposed reflecting ribs 16 and 17 to permit the user to readily see the levels of the 45 water in the compartments 11 and 12. The plates 14 and 15 are fastened in place by covers 18 and 19 fastened by bolts 20 and 21 to the body 10.

In practice, the sides of the body 10 are 50 provided with rabbets 22, 23 and similar rabbets 24, 25 are formed on the inner faces of the covers 18 and 19 to receive the glass plates 14 and 15 with a view to securely hold the plates in position. Suitable gaskets 55 26 and 27 are arranged in the rabbets 22,

23, and similar gaskets 28, 29 are arranged in the rabbets 24, 25 to render the gage steam and water tight. The gaskets 26, 27 are preferably made of copper, while the gaskets 28, 29 are preferably made of asbestos or a similar material. It is understood that when the covers 18 and 19 are screwed in place on the body 10 then the gaskets 26, 27, 28 and 29 are compressed to insure water and steam-proof joints between the body 10 and the plates 14 and 15. 60

The upper ends of the compartments 11 and 12 are provided with steam inlet pipes 30, 31 having valves 32, 33 adapted to be opened and closed independently whenever 70 it is desired to do so. Normally the valves 32 and 33 are, however, in open position. The pipes 30 and 31 are both connected with a valve 34 connected by a pipe 35 with the boiler 36 at the steam compartment thereof, 75 and the valve 34 is likewise normally open to allow steam to pass from the boiler through the pipe 35 and valve 34 and pipes 30, 31 and their valves 32, 33 into the upper ends of the two compartments 11 and 12. 80 The lower ends of the compartments 11 and 12 are provided with water inlet pipes 40, 41 provided with valves 42, 43 and both connected with a single valve 44 connected by a pipe 45 with the boiler 36 at the water 85 compartment thereof. The valves 44 and 42 are normally open so that water from the water compartment of the boiler passes into the lower portions of the compartments 11 and 12 to permit of viewing the water level 90 of the boiler independently in both compartments 11 and 12 through the corresponding glass plates 14 and 15. It will be noticed that by closing the valves 34 and 44 both the steam and the water in the boiler 36 95 are cut off from the gage. In case one of the plates 14 or 15 breaks or a leaky joint is formed at either compartment then this particular compartment can be cut out by correspondingly closing the valves 32, 42 100 or 33, 43.

When using the gage on a locomotive boiler, the body 10 has its sides converging from the back toward the front, as plainly indicated in Fig. 3, to permit the engineer 105 and the fireman in charge of the locomotive to readily observe the level of the water in the gage without the engineer and the fireman changing their respective positions. It will be noticed that the level of the water 110

in the boiler can be seen from either side of the gage and by providing the two compartments the gage can remain in service even if one of the glass plates 14 or 15 breaks. It is understood that in case the glass plate 14 or 15 breaks, the corresponding valves 32, 42 or 33, 43 are closed to shut off the steam and water from the corresponding compartment. The broken glass plate can now be removed and replaced by another without interfering with the use of the glass gage owing to the fact that the other compartment is still in service.

It will also be noticed that a gage constructed in the manner described is exceedingly strong and durable and is practically safe against blowing out, as is so frequently the case with the ordinary glass tube gages heretofore used. It will further be noticed that the danger of falling glass from a burst glass tube is completely eliminated.

Having thus described our invention, we claim as new and desire to secure by Letters Patent:—

25 1. A duplex boiler gage, comprising a body provided with two compartments having a partition in common and having diaphanous side plates and covers holding the

plates in position, and independent upper and lower valved gage connections at the upper and lower ends of the said compartments.

2. A duplex boiler gage, comprising a body provided with two compartments having a partition in common and having diaphanous side plates and covers holding the plates in position, independent upper and lower valved gage connections at the upper and lower ends of the said compartments, and valved boiler connections connecting with the said valved gage connections.

3. A duplex boiler gage, comprising a body provided with two compartments having a partition in common and having diaphanous side plates and covers holding the plates in position, independent upper and lower valved gage connections at the upper and lower ends of the said compartments, a single valve boiler connection connected with the said upper gage connection, and a single valve boiler connection connected with the said lower gage connection.
